CIRCUIT INTERRUPTER

Jerome M. Sandin, Forest Hills, Pa., assignor to
 Westinghouse Electric & Manufacturing Company, East Pittsburgh, Pa., a corporation of Pennsylvania

Application September 12, 1935, Serial No. 40,194

30 Claims. (Cl. 200—98)

My invention relates generally to electrical apparatus and particularly to circuit breakers of the type which are used for controlling industrial power distribution and secondary network circuits.

5 Circuit breakers for this type of service must meet a number of rather exacting and to some extent conflicting requirements, and their design has always presented a rather complex problem to the art. Due to the large amounts 10 of available power which may be fed into the circuit upon the occurrence of fault conditions, it is necessary, to give adequate protection to the controlled equipment, that the breakers shall 15 be capable of interrupting large amounts of power within very short intervals of time. Further, since the devices are ordinarily operated by more or less inexperienced persons, it is imperative that they shall be absolutely safe and 20 reliable in operation.

In order to prevent undesirable discontinuities in service while at the same time providing satisfactory protection of the controlled circuits and the connected equipment, it is necessary that 25 the breakers shall be capable of distinguishing between prolonged overloads and those of a transient nature. In addition, it is necessary, in certain installations, that the equipment shall be responsive to abnormal voltage conditions and 30 that it may be actuated by remotely disposed control means of the relay or other type.

In contrast with these operational requirements, it is absolutely imperative that the physical dimensions of these breakers shall be kept 35 within certain defined limits, in order to permit their use in existing panelboard and other switch structures. In addition, it is necessary that the initial cost of the breakers shall not be excessive, due to the large numbers which 40 are used on even a small system or network, and it is desirable that the breakers shall be easy to service in order to minimize maintenance costs. The provision of a breaker which is capable of meeting all of these requirements constitutes the principal object of the present invention.

One form of breaker which has met with considerable success in the past utilizes a single 45 standardized contact structure and actuating mechanism for a rather wide range of current values, the rating of any particular breaker being determined by the provision of a suitable trip device. The closure for these breakers comprises a cooperating base and cover, preferably 50 formed of molded insulating material. By means

of suitable ribs and partitions in the multi-pole forms, a separate space or chamber is provided for each of the poles. The movable contacts for the several poles are mechanically tied together so as to move as a unit, and a single 5 operating mechanism, normally disposed in one of the pole spaces, is utilized for actuating all of the contacts.

The trip device for the multi-pole breakers extends across all of the poles thereof and is 10 adapted to engage and be retained within a suitable recess formed in the cooperating cover and base. The device includes tripping means operable in response to predetermined electrical 15 conditions in the circuit controlled by each of the poles of the breaker. By making the trip device readily interchangeable with other similarly proportioned device, it is possible to market a whole line of breakers built up around 20 the single, standardized, contact structure and actuating mechanism.

For most installations, it is necessary to provide but two tripping means for each of the poles of the breaker, one a thermally responsive element operable after a predetermined time delay upon the occurrence of a prolonged moderate overload to effect the operation of the trip device and the other operable substantially instantaneously upon the occurrence of predetermined large magnitude overloads. In other 25 installations, it is also necessary to provide under-voltage tripping means, shunt tripping means, and similar arrangements. The incorporation of auxiliary devices of these latter types into the known forms of circuit breaker and trip devices through the utilization of the unoccupied portion of the pole chambers constitutes a 30 further object of the present invention.

Another object of the invention consists in the provision of means for cooperating with the 40 actuating mechanism for controlling the operation of auxiliary tripping devices.

A further object of the invention is to provide a removable trip device interchangeable with similar devices of like or different rating for 45 controlling the operation of circuit breakers which may be calibrated and sealed at the factory and to which, at the option of the user, may be added additional tripping means or other auxiliary devices without necessitating the 50 opening of the closure for the trip device, with the accompanying danger that the calibration thereof might be changed.

A still further object of the invention is to 55 provide an interchangeable trip device of the

type which includes a separate sealed closure for the movable portions thereof and which is removable as a unit from cooperative engagement with the associated breaker mechanism with non-adjustable tripping means adapted to operate in conjunction with the normal tripping means of the breaker. These additional tripping means to be disposed without the closure of the trip device.

An ancillary object of the invention is to provide an improved shunt trip element and an improved under-voltage trip element for a circuit breaker trip structure of the type under discussion, and to provide a simple means for controlling the operation of such devices in response to the operation of the associated breaker actuating mechanism and contact structure.

These and other objects will be made more apparent by reference to the following drawings and descriptions of certain preferred embodiments of the invention. Referring particularly to the drawings:

Figure 1 is a plan view of a three-pole circuit breaker wherein are embodied the features of the invention. The cover of the breaker has been almost completely cut away in order to more clearly illustrate the various structural elements.

Fig. 2 is an enlarged sectional view taken on the line II—II of Fig. 1.

Fig. 3 is a fragmentary view of the trip device and a portion of the operating mechanism of the breaker illustrated more completely in Figs. 1 and 2.

Fig. 4 is an enlarged sectional view of the trip device shown in the other figures of the drawings. The view is taken on the line IV—IV of Fig. 3.

Fig. 5 is an enlarged view of the shunt trip element forming a part of the trip device shown particularly in Figs. 1 and 2.

Fig. 6 is a sectional view on the line VI—VI of Fig. 5.

Fig. 7 is a view corresponding to Fig. 6, showing the features of the under-voltage trip element forming a part of the trip structure shown particularly in Figs. 1 and 2.

Fig. 8 is an enlarged fragmentary view, partially in section, of the operating linkage utilized in conjunction with the under-voltage trip element, and

Fig. 9 is a fragmentary enlarged view of the trip bar and portions of the bimetallic thermally responsive trip elements forming a part of the trip device proper.

The circuit breaker illustrated particularly in Figs. 1 and 2 is, as mentioned above, of the three pole type. The base 1 upon which all of the structural features of the breaker are mounted is formed of molded insulating material and is provided with suitable ribs or partitions 3 formed integral therewith for separating the three poles. The cover 5 is likewise formed of molded insulating material and is provided with cooperating ribs 7, as is shown particularly in Fig. 2, for engaging the similarly disposed ribs 3 in the base. In the completed structure, these ribs or partitions 3 and 7 serve to define three chambers which have the substantial form of rectangular prisms and which are spaced side by side.

70 Six terminals 9, three of which are affixed to either end of the base by means of suitable bolts 11 provide a means whereby the breaker may be connected into an electrical circuit. The electrical circuit through each of the poles of the breaker is substantially the same. A rigid strap

member 13 of conducting material, preferably copper, serves to support each of the stationary contact members 15 and to connect those members with the adjacent cooperating terminal 9. A movable contact member 17 pivotally supported upon a suitable frame 19 is provided for cooperating with each of the stationary contacts 15. Two contact pressure securing springs 21, disposed intermediate each of the movable contacts 17 and the supporting frame 19 therefor assure a 10 resilient engagement between each pair of cooperating contacts. A flexible conductor 23 formed of laminated material is electrically and mechanically connected to the rear end of each of the movable contacts 17, and each of these 15 flexible conductors 23 terminates in a solid terminal member 25 which is adapted to cooperate with one of the terminals 29 of the breaker trip device 27.

As is shown particularly in Figs. 1 and 2, the trip device 27 is provided with six of these terminals 29, two for each of the poles of the breaker. Each pair of the terminals 29 is electrically interconnected within the device itself by a looped conducting strip 31, formed of laminated material, which serves as an energized heater for the thermally responsive trip element and as an energizing coil for the magnetically responsive trip element associated with each of the poles of the trip device. Each of the upper terminals 29 of the trip device 27 is affixed to one of the block terminal members 25 by means of a pair of screws 33 and each of the lower terminal members is in turn affixed to one of the terminals 9 of the breaker by a pair of the bolts 11. Thus, the conducting strip 31 interposed between each of the pairs of terminals of the trip device serves to complete the electrical circuit for each of the poles of the breaker from the terminal member 25 to the lower breaker terminal 9.

Each of the contact supporting frames 19 is bolted to a square tie member 35, comprising a steel core and an outer sheath of insulating material, in order to permit the simultaneous actuation of the contacts. A single operating mechanism 37 is provided for simultaneously actuating the contacts.

The contact supporting frame 19 for the central pole has a link member 39 cast integral therewith, and this link member is pivotally supported upon the frame 41 of the actuating mechanism 37 by a suitable pivot pin 43, the pin 43 thus serving to support the entire assemblage of interconnected movable contacts. The operating mechanism 37 is preferably of the type disclosed in the copending application of Harry J. Lingal, Serial No. 637,749, filed October 14, 1932, which became Patent No. 2,083,305 on June 8, 1937 and which is assigned to the assignee of the present invention. As illustrated in Fig. 2, the 60 mechanism includes a pair of toggle links 45 and 47, an operating member 49, an over-center spring 51 intermediate the operating member and the toggle links for causing those links to move from the normal closed circuit position shown in Fig. 2 65 to a collapsed open circuit position, or vice versa, in response to movement of the operating member 49. One end of the interconnected toggle links is supported upon a cradle member 53 which is normally retained in the position shown in Fig. 70 2 by a trigger member 55 adapted to engage and cooperate with the trip device 27. The trip device normally retains the trigger member 55 in the position shown in Fig. 2, and when the trigger is in that position the actuating mechanism 75

37 is operable in response to movement of the operating handle 49 to move the interconnected movable contacts 17 to the open and to the closed circuit position.

5 Upon the actuation of the trip device, the trigger member 55 is released, and it moves automatically to a position where it causes the actuating mechanism 37 to effect the opening of the breaker, independently of the position of the operating handle 49. By virtue of the overcenter spring construction, the contacts are at all times moved to the open, to the closed and to the tripped position, (which is substantially the same as the open position) with a snap action.

15 The various structural elements of the trip device 27 are mounted upon a separate base member 51 which is adapted to engage a suitable recess 59 formed within the cooperating base 1 and cover 5 which comprise the breaker closure. The 20 device includes a latch 61, which is shown particularly in Fig. 4 for engaging and retaining the trigger member 55 of the breaker actuating mechanism in its normal operative position, a trip bar 62 movable from a normal inoperative position to an operative position to release the latch 61 and effect the operation of the trip device, a plurality of thermally responsive, trip elements, each of which is energized in response to the current flow in one of the poles of the breaker, and a plurality of magnetically responsive trip elements each of which is likewise energized in response to the current flow in one of the poles of the breaker. Each of the thermally responsive trip elements and each of the magnetically responsive trip elements is individually operable upon the occurrence of predetermined conditions to move the trip bar 62 from the normal inoperative position, shown in Fig. 4, to a position where it causes the latch member 61 to release the trigger member 55 and thus effect the opening of the breaker. The trip bar 62 is pivotally supported at either of its ends upon suitable bracket members 65 affixed to the base 51 of the trip device and extends across all three of the poles of the breaker. It is biased to its normal position by a suitable spring 67 and since the latch 61 is also biased to the normal latched position, the trip device is automatically resettable after each operation thereof.

Each of the thermally responsive elements comprises a tapered strip of bimetallic material 68 which is supported at one end thereof upon a U-shaped frame member 69, the frame member being, in turn, bolted to the base 51 of the trip device. The looped portion of the laminated conductor 31 disposed between each of the pairs of terminals 29 of the trip device extends along the bimetallic member 68 and is affixed to the lower end thereof and to the supporting U-shaped frame 69 therefor by means of a pair of rivets 71. The upwardly extending portion of the bimetallic element 68 is provided with an adjustable screw 73 for engaging the trip bar 62.

Each of the magnetically responsive elements includes a U-shaped core member 75 supported upon the adjacent U-shaped frame 69, and a slidably supported armature 17 biased away from the cooperating core member 75 by a pair of springs 79. The core member is energized by current flow through the associated looped conductor 31, and the springs 79 are so adjusted that movement of the armature takes place only following the occurrence of predetermined severe overload conditions. The trip bar 62 is provided with three downwardly projecting members 81, one of which is disposed in the normal path of

movement of each of the armatures 17, in order that movement of the armatures may be transmitted to the trip bar. Thus, the trip bar may be moved from the normal inoperative to the tripped or operative position by the bending of any one of the bimetallic elements 68 or by the movement of any one of the slidable armatures 17 from the unattracted to the attracted position.

5 A support bracket 83 is rigidly affixed to the base 51 of the trip device at the central portion thereof, and this bracket is provided with a pin 84 adapted to engage a suitable recess 86 formed in the block terminal 25 of the central pole in order to accurately position the trip device 27 with respect to the other features of the breaker 15 mechanism. This bracket 83 also serves to support and accurately position the trip latch 61.

A removable cover 85, formed of molded insulating material, is provided for enclosing the various structural features of the trip device. 20 This cover is normally supported upon the brackets 65 by means of suitable screws 87 and these screws are preferably sealed in position by a seal 88 as is shown in Fig. 3, during the manufacture of the device, in order to prevent unauthorized persons from tampering with the calibration of the trip elements.

In addition to the above-mentioned thermally responsive and magnetically responsive trip elements, the device shown in the drawings is further provided with a shunt trip element 91 and an under-voltage trip element 93. Each of these elements is supported upon the base 51 of the trip device by means of a suitable bracket member 95 and a pair of bolts 97, and each is readily removable therefrom without necessitating the removal of the cover 85 of the trip device. The bracket members 95 are so arranged that they support the under-voltage and the shunt trip elements a substantial distance away from the base 51 of the trip device and thereby assure that the addition of either or both of these elements shall in no way interfere with the removal or replacement of the trip device by preventing free access to the removable screws 33 utilized for connecting the trip device into the breaker structure.

40 The shunt trip element 91 is shown particularly in Figs. 5 and 6. It includes a U-shaped core 101 of magnetic material rigidly affixed to, 50 or formed integral with, the supporting bracket 95. An iron pole piece 103 is screwed into a suitable recess formed in the outer end of this U-shaped core 101, and a brass tube 105 which serves as a guide for the movable armature 107 55 of the element engages a suitable supporting shoulder formed in this pole piece. The inner end of the brass tube 105 is retained in position by a cap member 109 which serves the further function of providing a stop for the armature. 60 The armature 107 is cylindrical in form and is provided with a hollow cylindrical recess 111 formed in the outer end thereof for positioning a suitable biasing spring 114. The coil means 113 for energizing the pole piece of the device is 65 disposed about the brass tube 105 and is insulated from metallic portions of the device by an insulating spool 115. A tie-rod 117, preferably of insulating material, is affixed to the inner end of the armature 107 and is provided with a C-shaped member 118 for engaging one of the projections 119 forming a part of the trip bar 62. This rod and the C-shaped trip bar engaging member 118 move within a suitable hole 121 70 formed within the base 51 of the trip device. The 75

armature is normally biased to the untripped position by the spring 114.

In order to prevent burning out of the energizing coil 113 during the operation of the shunt trip element, an auxiliary switch 123 is provided for opening the electrical circuit through the coil as soon as the breaker contacts have been moved to the open circuit position. This switch 123, as is shown particularly in Figs. 5

10 and 6, comprises a base 125 of molded insulating material which is affixed to the core 101, a pair of strap conductors 127 disposed within suitable recesses formed therein, and a third strap member 129 for bridging the members 127. The bridging member 129 is supported for movement into and out of bridging engagement with the straps 127 by means of a slidable rod member 131 of insulating material having a head 133 formed integral therewith. This insulating support member 131 is biased to the closed circuit or bridging position by means of a spring 135 and is adapted to be moved so as to open the electrical circuit through the switch by the engagement of an L-shaped member 137 affixed to the contact supporting frame 19 for the outer pole. Through this arrangement, the electrical circuit through the energizing coil 113 for the shunt trip element 91 is opened at two points, immediately upon the movement of the breaker contacts to the open

30 circuit position, and any danger of the coil being burned out is thereby eliminated.

The under-voltage trip element 93 is shown particularly in Fig. 7. Similar to the shunt trip element 91, it includes a U-shaped frame 201 of magnetic material formed integral with the supporting bracket 95 therefor. The pole piece 203 is threaded into the inner side of the U-shaped frame 201, as contrasted with the pole piece 103, due to the difference in the direction of movement of the armatures. The armature 207 is cylindrical in form, is provided with a suitable biasing spring 214 for directing it away from the pole piece 203, and is adapted to move within a brass tube 205 ordinarily retained in abutting engagement with a shoulder formed in the pole piece by an outer cap member 209. The armature 207 includes an inwardly extending rod 216 adapted to operatively engage the tie rod 117 and the C-shaped member 118 which comprise the trip bar engaging means, substantially the same as for the shunt trip element. A suitable voltage responsive energizing coil 213 serves to retain the armature 207 in the position shown in Fig. 7 except when the energizing voltage falls 55 below a predetermined minimum value.

In order to assure that the armature of the under-voltage element shall be moved into contact with the cooperating pole piece following each operation of the breaker, a mechanical linkage means is provided for interconnecting the armature with the breaker contact assemblage. This linkage includes a rigid metallic member 221 affixed to the supporting frame 19 for the right-hand movable contact member, an insulating link 223, and a spring plunger means affixed to the armature 207 itself. The plunger means comprises a rod member having an enlarged outer portion 229 and an inner portion 231 of reduced area upon which a washer 233 is adapted 60 to slide, this washer being normally biased against the shoulder formed by the enlarged outer end 229 by a suitable spring 235. The intermediate link 223 has a cylindrical guide opening 237 of somewhat larger diameter than the 70 outer end 229 to assure the movement of the rod

member therein, and when the contacts move to the open circuit position, this intermediate member engages the slidable washer 233 and moves that washer to a position where the stress transmitted through the spring 235 is sufficient to restore the armature 207 to its normal position. In this position the impedance of the device reaches its maximum value and burning out of its energizing coil 213 upon the restoration of voltage to the energizing circuit is prevented.

The operation of the trip device 27 is believed to be more or less obvious from the foregoing. Upon the occurrence of a predetermined low magnitude overload in the circuit controlled by any one of the poles of the breaker and the persistence of that overload for a predetermined period of time, the bimetallic element 68, energized in response to the current flow in that pole, is caused to bend and move the trip bar 62 to the operative position. In this position the latch 61 no longer restrains the trigger member 55 in the position shown in Fig. 2 and the trigger member moves automatically to cause the actuating mechanism 37 to effect the opening of the breaker irrespective of the position of the operating handle 49. Similarly, upon the occurrence of a predetermined large magnitude overload in the circuit controlled by any one of the poles of the breaker, the associated core member 75 is energized sufficiently to attract the cooperating armature 77 and thereby move the trip bar 62 from the normal inoperative to the tripped position.

The thermally responsive and the magnetically responsive trip elements provide complete overload protection for the circuits controlled by the breaker, but they do not give protection against under-voltage or over-voltage conditions nor do they permit remote control of the breaker. These latter functions are accomplished by the shunt trip element 91 and the under-voltage trip element 93. In the shunt trip element the armature is moved magnetically, in the under-voltage element the armature is restrained from movement by an electromagnetic field. Together the elements provide a flexible arrangement capable of meeting all possible requirements.

Both elements may be added to a trip device of the type disclosed in the subject application without necessitating the removal of the cover of that device. Factory adjustments and calibrations are thus preserved throughout the operative life of the device. In both elements the armature engages the trip bar only during the latter portion of its movement from the inoperative to the operative position. This assures positive actuation of the trip bar by permitting the armature to acquire substantial kinetic energy before engaging and moving that member.

The lead terminals 251 of the shunt and under-voltage trip elements are preferably brought out of the breaker closure through suitable holes 253 formed in the side walls of the base member 1.

From the foregoing, it will be seen that I have disclosed the features of a new and improved form of electro-responsive trip device, particularly suitable for use with circuit breakers of the type which employ standard operating mechanisms and interchangeable trip structures. In addition, I have disclosed auxiliary tripping means such as under-voltage and shunt trip devices which may be added to known forms of trip structures without necessitating the removal of the covers of those devices or without neces-

sitating any substantial alteration in the associated equipment.

In the preferred form of my invention, I so position these auxiliary tripping means on the base of the trip device that they extend into the space ordinarily left unoccupied when the breaker is in operation, that is, within the excess space in the chambers provided for each of the poles. This probably is one of the most important features of the present invention because it is only by this novel arrangement that the use of these auxiliaries in conjunction with existing equipment is made possible.

It will immediately be obvious that my provision of auxiliary control means for tripping devices and my improved arrangement of the structural features of these devices has effected a substantial extension of the useful range of operation of these devices without any accompanying deleterious effects whatsoever. The resultant trip devices are still readily interchangeable, and their normal operational qualities are in no way effected by the addition of the auxiliary means in accordance with the invention.

Further, I have disclosed certain preferred structural arrangements for accomplishing the other objects of the invention, and I have shown how the operation of my improved under-voltage and shunt trip device may be controlled by the operating mechanism and the contacts of the breaker.

While in accordance with the patent statutes, I have, in the foregoing, disclosed the features of certain preferred structural arrangements and embodiments of my invention, it is to be understood that these structures are merely illustrative. Variations in their precise form may and probably will be not only desirable but necessary in many instances without departing from the concept of the invention and it is my desire, therefore, that the language of the accompanying claims shall be accorded the broadest reasonable construction and shall be limited only by what is expressed therein and by the prior art.

I claim as my invention:

1. In a circuit interrupter, separable contact means for opening and for closing the electrical circuit therethrough, actuating means for said contact means, a trip device operable upon the occurrence of predetermined conditions to cause said actuating means to move said contact means automatically to the open circuit position, said trip device being removable from said interrupter as a unit and including a base, a cover which operates with said base to define a closure for said device, electro-responsive tripping means disposed within said closure, and other electro-responsive tripping means supported on said base outside said closure, said last mentioned means being removable from operative engagement with said trip device without necessitating the removal of said cover, and means for mechanically interconnecting said last mentioned tripping means with said separable contact means and the actuating means therefor.

2. In a circuit interrupter; separable contact means for opening and for closing the electrical circuit therethrough; actuating means for said contact means; and a trip device operable upon the occurrence of predetermined conditions to cause said actuating means to move said contact means automatically to the open circuit position; said trip device being removable from said interrupter as a unit and including a sealed closure, electro-responsive tripping means disposed within

said closure, and auxiliary tripping means disposed outside said closure; said last mentioned means being readily removable from operative engagement with said trip device without necessitating the opening of said sealed closure, to permit similar means of like or different characteristics to be substituted therefor.

3. A trip device for a circuit interrupter comprising a unitary structure removable as a unit from said interrupter and including a base, a cover for cooperating with said base to define a closure for said device, terminals mounted on said base for releasably connecting said device into the electrical circuit or circuits controlled by the associated interrupter, electro-responsive tripping means disposed within said closure, and auxiliary electro-responsive tripping means supported on said base outside said closure, said last mentioned tripping means being readily removable from and movable into operative engagement with said trip device without necessitating the removal of said cover, to permit similar means of like or different characteristics to be substituted therefor.

4. A trip device for a circuit interrupter comprising a unitary structure removable as a unit from said interrupter and including a base, a cover for cooperating with said base to define a closure for said device, terminals mounted on said base for releasably connecting said device into the electrical circuit or circuits controlled by the associated interrupter, electro-responsive tripping means disposed within said closure, and at least two auxiliary electro-responsive tripping means supported on said base outside said closure, one of said auxiliary tripping means including an armature biased to an operative position and electro-magnetic means for restraining said armature in an inoperative position, another of said auxiliary tripping means including an armature biased to an inoperative position and electro-magnetic means for moving said armature to an operative position, said auxiliary tripping means being interchangeable with each other and being removable from operative engagement with said trip device without necessitating the removal of said cover to permit similar means of like or different characteristics to be substituted therefor.

5. In a circuit interrupter; separable contact means for opening and for closing the electrical circuit therethrough; actuating means for said contact means; a trip device operable upon the occurrence of predetermined conditions to cause said actuating means to move said contact means automatically to the open circuit position; said trip device being removable from said interrupter as a unit and including a sealed closure, electro-responsive tripping means disposed within said closure, and at least two auxiliary electro-responsive tripping means disposed outside said closure; one of said auxiliary tripping means including an armature biased to an operative position and electro-magnetic means for retaining said armature in an inoperative position; another of said auxiliary tripping means including an armature biased to an inoperative position, a current-carrying attracting coil for moving said armature to an operative position, and a switching means electrically connected in series with the circuit through said attracting coil; said auxiliary tripping means being interchangeable with each other and being removable from operative engagement with said trip device without necessitating the opening of said closure, to permit similar means of like or different characteristics

- to be substituted therefor; and means for mechanically interconnecting said auxiliary tripping means with said contact means and said contact actuating means, in order that the armature of
- 5 said first mentioned auxiliary tripping means shall be restored to said inoperative position in response to each opening movement of said contact means resulting from movement of that armature to said operative position, and in order
- 10 that the operation of said switching means forming a part of said last mentioned tripping means shall be caused to take place in response to movement of said contact means.
6. In a multi-pole circuit interrupter; a base;
- 15 a cover for cooperating therewith to define a closure for said interrupter; conducting means including a plurality of pairs of separable contacts for defining the plurality of poles of said interrupter; means for dividing said closure into
- 20 a plurality of separate chambers, one for each of said poles; the conducting means for each of said poles being disposed in one of said chambers; a single actuating means for a plurality of said pairs of separable contacts, said actuating means
- 25 being disposed within one of said pole chambers; and a trip device operable to cause said contact actuating means to move said plurality of pairs of separable contacts automatically to the open circuit position, said trip device being disposed
- 30 within said closure for said interrupter and removable from said closure as a unit, said unit including a separate closure, electro-responsive tripping means disposed within said separate closure, and other electro-responsive tripping
- 35 means disposed without said separate closure; said last mentioned tripping means being readily removable from operative engagement with said trip device, without necessitating the opening of said separate closure, to permit similar means of
- 40 like or different characteristics to be substituted therefor, and being adapted to extend into one or more of said chambers when said trip device is in the normal operative position within said main closure.
- 45 7. In a multi-pole circuit interrupter; a base; a cover for cooperating therewith to define a closure for said interrupter; conducting means including a plurality of pairs of separable contacts for defining the plurality of poles of said interrupter; cooperating partition or rib members
- 50 formed integral with said base and said cover for dividing said closure into a plurality of separate chambers, one for each of said poles; the conducting means for each of said poles being disposed in one of said chambers; a single actuating mechanism for said plurality of pairs of separable contacts, said actuating mechanism being disposed within one of said pole chambers; and a trip device operable to cause said contact actuating
- 55 means to move said plurality of pairs of separable contacts automatically to the open circuit position, said trip device being disposed in a suitable recess formed within said closure for said interrupter and removable therefrom as a unit,
- 60 said unit including a separate, sealed closure adapted to extend across said pole chambers adjacent one of the ends thereof, electro-responsive tripping means disposed within said sealed closure, and auxiliary tripping means disposed without
- 65 said sealed closure; said auxiliary tripping means being readily removable from operative engagement with said trip device, without necessitating the opening of said sealed closure, to permit similar means of like or different characteristics to
- 70 be substituted therefor and being adapted to ex-

tend into one or more of said pole chambers when said trip device is in the normal operative position within said closure for said interrupter.

8. In a multi-pole circuit interrupter; a base; a cover for cooperating therewith to define a closure for said interrupter; conducting means including a plurality of pairs of separable contacts for defining the plurality of poles of said interrupter; cooperating partition or rib members formed integral with said base and said cover for dividing said closure into a plurality of separate chambers, one for each of said poles; the conducting means for each of said poles being disposed in one of said chambers; a single actuating mechanism for said plurality of pairs of separable contacts, said actuating mechanism being disposed within one of said pole chambers; a trip device operable to cause said contact actuating means to move said plurality of pairs of separable contacts automatically to the open circuit position, said trip device being disposed in a suitable recess formed within said closure for said interrupter and removable therefrom as a unit, said unit including a separate closure adapted to extend across said pole chambers adjacent one of the ends thereof, electro-responsive tripping means disposed within said closure, and auxiliary tripping means disposed without said closure; said auxiliary tripping means being adapted to extend into one or more of said pole chambers when said trip device is in the normal operative position within said closure for said interrupter; and means for mechanically connecting said auxiliary tripping means with said separable contacts and said contact actuating means, said connecting means including means movable in one or more of said pole chambers.

9. In a circuit interrupter, separable contact means for opening and for closing the electrical circuit therethrough, actuating means for said contact means, a trip device operable upon the occurrence of predetermined conditions to cause said actuating means to move said contacts automatically to the open circuit position, said trip device being removable from said interrupter as a unit and including a base, a cover which cooperates with said base to define a closure for said trip device, electro-responsive tripping means disposed within said closure, and other electro-responsive tripping means disposed without said closure and having a connecting member extending into the closure to operate the trip device, and means for mechanically connecting said other tripping means outside the closure with said separable contacts and said actuating means therefor for rendering said other electro-responsive tripping means inoperative when the contacts are in the open position.

10. In a circuit interrupter; separable contact means for opening and for closing the electrical circuit therethrough; actuating means for said contact means; a trip device mounted at one end of said actuating means and operable to cause said actuating means to move said contact means automatically to the open circuit position; said trip device being removable as a unit from operative engagement with the other elements of said interrupter and including a base, a cover which cooperates with said base to define a closure for said trip device, current-carrying electro-responsive tripping means disposed within said closure, and other current-carrying electro-responsive tripping means disposed outside said closure and beside said actuating means intermediate said trip device and said separable contact means, and

- an auxiliary switching means disposed without said closure and beside said actuating means intermediate said trip device and said separable contact means, said auxiliary switching means being electrically connected in series with the circuit through one of said current-carrying tripping means; and means for effecting the actuation of said auxiliary switching means in response to the opening and the closing movement 10 of said contact and said contact actuating means.
11. In a circuit interrupter; separable contact means for opening and for closing the electrical circuit therethrough; actuating means for said contact means; a trip device operable to cause 15 said actuating means to move said contact means automatically to the open circuit position; said trip device being removable as a unit from operative engagement with the other elements of said interrupter and including an electro-magnetic 20 tripping means which comprises an armature movable from a normal inoperative to an operative position to effect the operation of said trip device; and resilient connecting means connected 25 between said contact means and the aforesaid armature to permit lost motion between said contact means and said armature and operable, when said contact means is moved to the open circuit position in response to an operation of said trip device caused by movement of said armature to 30 said operative position, to return said armature to said inoperative position.
12. In a circuit interrupter; separable contact means for opening and for closing the electrical circuit therethrough; actuating means for said 35 contact means; a trip device operable to cause said actuating means to move said contact means automatically to the open circuit position; said trip device being removable as a unit from operative engagement with the other elements of said 40 interrupter and including an armature movable from a normal inoperative to an operative position to effect the operation of said trip device, means biasing said armature to said operative position, and electro-magnetic means for holding 45 said armature in said inoperative position against the force of said biasing means; said electro-magnetic means permitting said biasing means to move said armature to said operative position following the occurrence of predetermined 50 conditions; and resilient means mechanically interconnecting said movable armature with said contact and said contact actuating means, said resilient means causing said armature to be returned to said inoperative position following each 55 operation of said trip device resulting from movement thereof and permitting said contact and said contact operating means to continue movement after said armature has reached said inoperative position.
13. In a circuit breaker having separable contact members, actuating means for operating said contact members to open and closed positions and tripping means for causing said actuating means to operate said contact members to the open position 60 upon the occurrence of predetermined conditions, said tripping means comprising the combination with a sealed calibrated trip device removable as a unit from said breaker of an auxiliary trip actuating means, said auxiliary trip 65 actuating means being removable from and replaceable in operative engagement with said trip device without disturbing the seal of the latter.
14. In a circuit breaker having separable contact members, actuating means for operating said contact members to open and closed positions and 70
- 75
- tripping means for causing said actuating means to operate said contact members to the open position upon the occurrence of predetermined conditions, said tripping means comprising the combination with a sealed calibrated trip device removable as a unit from said breaker of an auxiliary current-responsive trip actuating element, said element being removable from and replaceable in operative relation with said trip device without disturbing the calibration of the latter, 10 switching means in circuit with said auxiliary current-responsive trip actuating element, and means operable upon the movement of said contact members for actuating said switching means.
15. In a circuit breaker having separable contact members, actuating means for operating said contact members to open and closed positions and tripping means for causing said actuating means to operate said contact members to the open position upon the occurrence of predetermined conditions, said tripping means comprising the combination with a sealed calibrated trip device removable as a unit from said breaker of an auxiliary current-responsive trip actuating element, 15 said element being removable from and replaceable in operative relation with said trip device without disturbing the calibration of the latter, switching means in circuit with said auxiliary current-responsive trip actuating element, and control means adapted to be actuated by said 20 actuating means for said contact members for operating said switch means to deenergize said auxiliary current-responsive trip actuating element when said contact members are in the open position.
16. In a circuit breaker having separable contact members, actuating means for operating said contact members to open and closed positions and tripping means for causing said actuating means to operate said contact members to the open position upon the occurrence of predetermined conditions, said tripping means comprising the combination with a sealed calibrated trip device removable as a unit from said breaker of an auxiliary current-responsive trip actuating element, 25 said element being removable from and replaceable in operative engagement with said trip device without disturbing the seal of the latter, and means actuated by said actuating means for said contact members for rendering said auxiliary 30 current-responsive trip actuating element inoperative when said contact members are in the open position.
17. The combination with a trip device for a multi-pole circuit breaker, said trip device being removable from said breaker as a unit and including a trip bar which is movable for causing the automatic operation of the circuit breaker contacts to the open position and a calibrated current-responsive element for each pole adapted to 35 actuate said trip bar upon the occurrence of predetermined conditions of one or more auxiliary current-responsive elements operable upon the occurrence of other predetermined conditions to 40 actuate said trip bar, said auxiliary current-responsive elements being removable from and replaceable in operative relation with said trip device without disturbing the calibration of said first-named current-responsive elements.
18. The combination with a trip device for a 45 multi-pole circuit breaker, said trip device being removable from said breaker as a unit and including a trip bar normally biased to a latching position for retaining the circuit breaker contact operating mechanism in the closed position 50
- 55
- 60
- 65
- 70
- 75

- and a calibrated movable current-responsive element for each pole, said trip bar having a projection for each pole adapted for operative engagement with a current-responsive element for movement thereby to the tripped position upon the occurrence of predetermined conditions of one or more auxiliary current-responsive elements operable upon the occurrence of other predetermined conditions, said auxiliary current-
 10 responsive elements having means operatively engaging at least one of said projections to actuate said trip bar to the tripped position independently of said calibrated current responsive elements, said auxiliary current-responsive elements being releasable from and replaceable in operative relation with said trip device without disturbing the calibration of said first-named current-responsive elements.
- 18 19. In a circuit interrupter, actuating means for opening and closing the circuit interrupter, an under-voltage trip device operable to cause said actuating means to open the circuit interrupter upon the occurrence of a predetermined under-voltage condition, said trip device including a member biased to move to tripped position and current-responsive means normally holding said member and releasing it upon the occurrence of said predetermined under-voltage condition, and connecting means including a resilient member positioned between said actuating means and said biased member and through which movement of said actuating means is transmitted to said biased member for returning it to position where it is held by the current-responsive means, said resilient member permitting greater movement of said actuating means than is required to return said biased member into operative relation with said holding means.
- 25 20. In a circuit interrupter, a base member, separable contact means for opening and closing the circuit through the circuit interrupter positioned on the base member adjacent one end thereof, actuating means for the contact means positioned directly against the base member adjacent the mid-portion thereof, a trip unit including current-responsive means positioned on the base member adjacent the other end thereof, an auxiliary trip device positioned in the space beside said actuating means and between said trip unit and said contact means, connecting means extending from said auxiliary trip device to said trip unit for actuating the trip unit upon operation of the auxiliary trip device, and means movable upon the operation of said actuating means to act on said auxiliary trip device.
- 35 21. In a circuit interrupter, a base member, separable contact means for opening and closing the circuit through the circuit interrupter positioned on the base member adjacent one end thereof, actuating means for the contact means positioned close to the base member adjacent the mid-portion thereof, a trip unit including current-responsive means positioned on the base member adjacent the other end thereof, an under-voltage trip device positioned in the space beside said actuating means and between said trip unit and said contact means, said under-voltage trip device including a coil and an armature biased to move to tripped position, an operating connection extending from said under-voltage trip device to said trip unit for actuating the trip unit upon movement of the armature to tripped position, and means movable upon the operation of said actuating means for engaging and resetting the under-voltage trip device after

each movement of the armature to tripped position.

22. In a circuit interrupter, a base member, separable contact means for opening and closing the circuit through the circuit interrupter positioned on the base member adjacent one end thereof, actuating means for the contact means positioned close to the base member adjacent the mid-portion thereof, a trip unit including current-responsive means positioned on the base member adjacent the other end thereof, a shunt trip device including a coil, an armature movable by the coil and a cut-off switch in series with the coil, all positioned in the space beside said actuating means and between said trip unit and said contact means, an operating connection extending from said shunt trip device to said trip unit for actuating the trip unit upon movement of said armature, and means movable upon the operation of said actuating means for operating said cut-off switch after each operation of the shunt trip device.

23. In a circuit interrupter, separable contact means, actuating means for causing said contact means to open and close the circuit, a trip unit including electro-responsive means operable to cause said actuating means to open the circuit, a housing enclosing said trip unit, an auxiliary trip device including a second electro-responsive means mounted outside of said housing, an opening in said housing, connecting means extending from said auxiliary trip device through said opening to actuate said trip unit by said second electro-responsive means, and said auxiliary trip device with said connecting means being removable from and replaceable in operative relation with said trip unit through said opening without opening said housing.

24. In a circuit interrupter, separable contact means for opening and closing the circuit, a mechanism for operating said contact means, a shunt trip device for causing the actuation of said operating means, said shunt trip device including an electro-magnet and a cut-off switch therefor mounted together to form a single unit, said shunt trip device including the electro-magnet and the cut-off switch being removable from and replaceable on the circuit interrupter as a unit, and means movable with said operating mechanism for actuating said cut-off switch when said operating mechanism has been caused to operate by the shunt trip device.

25. In a removable shunt trip unit for a circuit breaker, an electro-magnetic device including a coil, an armature movable by the coil, and a spring opposing said movement of the armature by the coil, a cut-off switch mounted on said electro-magnetic device to form a unitary structure therewith and including contacts connected in series with said coil, circuit breaker operating means extending from the armature for engaging and operating the circuit breaker, and an operating member for the cut-off switch engageable and movable by the circuit breaker.

26. In an under-voltage trip unit for a circuit breaker, a solenoid having an opening therethrough, an armature movable in said opening but normally held by the solenoid, biasing means for moving said armature when released by the solenoid, circuit breaker operating means extending from one end of said opening for engaging and operating the circuit breaker upon movement of the armature, and resetting means for returning said armature against said biasing means into position where it may be held by said

solenoid, said resetting means extending from the other end of said opening and being engageable and movable by means operable by the circuit breaker.

27. In an under-voltage trip unit for a circuit breaker, a solenoid having an opening therethrough, an armature movable in said opening but normally held by the solenoid, biasing means for moving said armature when released by the solenoid, circuit breaker operating means extending from one end of said opening for engaging and operating the circuit breaker upon movement of the armature, and resetting means for returning said armature against said biasing means into position where it may be held by said solenoid, said resetting means having a portion extending from the other end of said opening and being engageable and movable by the circuit breaker, and said resetting means including a member movable by the circuit breaker and a resilient connection between said member and the armature permitting said member to be moved by the circuit breaker a distance greater than the armature may be moved.

28. In a multi-pole circuit interrupter, a base member, a line terminal member for each of the poles of the circuit interrupter, said line terminal members being positioned at intervals across one end of said base, a second line terminal member for each of the poles of the circuit interrupter, said second line terminal members being positioned at intervals across the other end of said base, a plurality of separable contacts positioned at intervals across said base adjacent the line terminal members at one end of the base, a main trip device including current responsive tripping means for a plurality of said poles positioned at intervals across said base adjacent the line terminal members at the other end of said base, an actuating mechanism for said separable contacts positioned on said base intermediate said plurality of contacts and said main trip device, said actuating mechanism being of less width than the width of said main trip device and of less width than the width of said plurality of contacts, an auxiliary trip device positioned in the space beside said actuating mechanism and intermediate said plurality of contacts and said main trip device, and connecting means extending from said auxiliary trip device to said main trip device for actuating said main trip device upon operation of the auxiliary trip device.

29. In a multi-pole circuit interrupter, a base member, a line terminal member for each of the poles of the circuit interrupter, said line terminal members being positioned at intervals across one end of said base, a second line terminal member for each of the poles of the circuit interrupter, said second line terminal members being positioned at intervals across the other end of said base, a plurality of separable contacts positioned at intervals across said base adjacent the line terminal members at one end of the base, a

main trip device including current responsive tripping means for a plurality of said poles positioned at intervals across said base adjacent the line terminal members at the other end of said base, an actuating mechanism for said separable contacts positioned on said base intermediate said plurality of contacts and said main trip device, said actuating mechanism being of less width than the width of said main trip device and of less width than the width of said plurality of contacts, and under-voltage trip device positioned in the space beside said actuating mechanism and between said plurality of contacts and said main trip device, said under-voltage trip device including a coil and an armature biased to move to tripped position, an operating connection extending from said under-voltage trip device to said main trip device for actuating said main trip device upon movement of said armature to tripped position, and means movable upon operation of said actuating mechanism for resetting the under-voltage trip device after each movement of the armature to tripped position.

30. In a multi-pole circuit interrupter, a base member, a line terminal member for each of the poles of the circuit interrupter, said line terminal members being positioned at intervals across one end of said base, a second line terminal member for each of the poles of the circuit interrupter, said second line terminal members being positioned at intervals across the other end of said base, a plurality of separable contacts positioned at intervals across said base adjacent the line terminal members at one end of the base, a main trip device including current responsive tripping means for a plurality of said poles positioned at intervals across said base adjacent the line terminal members at the other end of said base, an actuating mechanism for said separable contacts positioned on said base intermediate said plurality of contacts and said main trip device, said actuating mechanism being of less width than the width of said main trip device and of less width than the width of said plurality of contacts, a shunt trip device including a coil and an armature movable thereby positioned in the space beside said actuating mechanism and between said plurality of contacts and said main trip device, an operating connection extending from said shunt trip device to said main trip device for actuating said main trip device upon movement of said armature to tripped position, a cut-off switch connected in series with said coil and positioned in the space beside said actuating mechanism and between said plurality of contacts and said main trip device, and means movable upon the operation of said actuating mechanism for operating said cut-off switch after each operation of the shunt trip device.

JEROME M. SANDIN.
